DESIGN FOR AN AIRPLANE

Calvin N. White, Bakersfield, Calif.

Application June 8, 1942, Serial No. 107,156

Term of patent 14 years

To all whom it may concern:

Be it known that I, Calvin N. White, a citizen of the United States of America, residing at Bakersfield, in the county of Kern and State of California, have invented a new, original, and ornamental Design for an Airplane, of which the following is a specification, reference being had to the accompanying drawings, forming a part thereof.

Fig. 1 is a top plan view of an airplane showing my new design,

Fig. 2 is a side elevational view of the same,

Fig. 3 is a front elevational view, and

Fig. 4 is a top perspective view.

I claim:

The ornamental design for an airplane, as shown.

CALVIN N. WHITE.
